BED SPRING GAUGE

Huot W. Sternberg, Westport, and Rudolph O. Smith, Milford, Conn., assignors to The Owen Silent Spring Company, Inc., Bridgeport, Conn., a corporation of Connecticut

Application October 24, 1939, Serial No. 300,992

4 Claims. (Cl. 73—51)

This invention relates to a means employed in the manufacture of custom built cushion springs, more particularly bed springs.

In the ordinary commercial bed spring all of the springs are of the same stiffness except the springs along the edges which are frequently harder. It has been proposed to employ springs of different stiffness and/or height for the comfort of the average user without attempting custom building for the individual user. It has also been proposed to build bed springs with means for relatively raising and lowering the support of at least certain of the springs and the head and foot ends of the bed spring. None of the prior methods and means provide individualized custom built bed springs. Insofar as is known, no attempt has been made to build a bed spring for a double bed in which the springs on the sides of the center of the bed spring are adjusted or selected to suit the users.

An object of this invention is the provision of means for determining the stiffness of springs to be used in different sections of a bed spring or the like to provide for correct sleeping posture and individual comfort.

Other objects of the invention will appear from the following description taken in connection with the drawings, in which—

Fig. 1 is a top plan view of an apparatus which may be employed to carry out the method of this invention; and on which is supported a mattress partly broken away;

Fig. 2 is an end view of the apparatus looking upwardly in Fig. 1;

Fig. 3 is a vertical cross section on the line 3—3 of Fig. 1;

Fig. 4 is an enlarged view of the left hand end of Fig. 3;

Fig. 5 is a horizontal section on the line 5—5 of Fig. 4; and

Fig. 6 is a vertical longitudinal section taken on the line 6—6 of Fig. 1.

For the purpose of disclosure the drawings show a preferred form of bed spring gauge apparatus of this invention. This apparatus includes a rectangular frame 10 which may consist of a continuous L-shaped bar supported above the floor by means of legs 11 which may be of any suitable construction and as shown each leg may be formed from strip material of rectangular cross section bent into the form of a U with the cross element of the U resting on the floor and extending diagonally across the corner of the frame and with the legs twisted and riveted or otherwise secured to the vertically extending

flange of the L-shaped frame member. This apparatus includes a large number of springs preferably of the same number and located in the same positions as the springs of the bed spring to be constructed in accordance with the adjustment made on this apparatus. The row of springs 12 at the ends of the apparatus are supported directly on the frame 10 as indicated in Figs. 1 and 6 as it is not necessary to provide for adjustment of the springs in this position nor is it necessary to provide for adjustment of the row of springs 13 along the side of the apparatus, as the corresponding springs in the bed spring to be constructed are connected to upper and lower frame members and are preferably of the same stiffness.

The interiorly located springs generally designated as 14 are supported on and secured to bars 16 which may be of rectangular cross section and disposed as shown, connected by toggle links 17 and 18 to bars 19 which may be rectangular in cross section and disposed as shown, the ends of which may be twisted into a horizontal plane and bent upwardly and outwardly as indicated at 20 to rest on top of the lower frame 10 to which they may be secured by a nut and bolt as indicated at 21.

A pin 22 connecting the toggle links 17 and 18 together, passes through an interposed operating bar 23 to which is pivotally connected a link 24 pivotally connected to a nut 25 in which is threaded an adjusting bolt 26 supported in a generally L-shaped bracket 28 the horizontal portion of which is secured to the frame 10 preferably by the nut and bolt 21 which secures the bar 19 to the frame 10. The lower end of the bracket 28 is braced by means of a bar 29 connected thereto and to the bar 19 as indicated. The adjusting bolt 26 on each side of the bracket 28 is provided with a collar 30 and its outer end is fashioned as indicated at 31 to cooperate with an adjusting crank 32 by means of which the toggle operating bar 23 may be moved forward and rearward to open and close the toggle links 17, 18 to raise and lower the supporting bar 16 by means of which all the lower ends of the springs in a transverse row, except those at the sides of the apparatus, may be raised or lowered to increase or decrease their compression. The bar 19 is provided with a vertically extending bar 33 bearing indication marks preferably colored transverse bands of green, red, white and blue as indicated on the drawings which cooperate with a pointer 34 carried by the bar 16, the pur-

pose of which will be more clearly explained later on.

Supported on the upper ends of the springs 12 and 13 is a frame member 40 which may also be of L-shape in cross section disposed as shown. Connected to the sides and ends of this frame member are springs 41 to which are connected the ends of thin flexible strips 42 which extend diagonally of the apparatus and are connected by disks 43 overlying the interior springs 14. This provides a flexible support for a mattress 45 on which the customer reclines as the springs of the apparatus are adjusted. The springs may be interconnected by coiled springs 46 as disclosed in Figs. 3, 4 and 6. For the purpose of normally holding the upper ends of the springs in the same plane and for preventing these ends from moving upwardly as the lower ends thereof are raised by the adjusting devices, means in the form of a chain 48 may connect each disk 43 to the associated bar 19.

A bail shaped gauge 50 is pivoted to the end members of the frame 10 with its handle or cross rod 51 disposed lengthwise of and on top of the mattress.

In the use of the apparatus the customer reclines on the mattress in the usual position in which he is accustomed to sleep. The various adjusting rods 26 are operated to raise and lower ends of the springs of the various transverse rows in succession to aline the body center line horizontally and the bar 51 of the bail may be used as a gauge to facilitate this adjustment. After this has been done the rows of springs under the mattress near the head and foot ends of the apparatus are adjusted until the head and legs of the customer are brought into alinement with the body of the customer, the bail for this purpose being raised centrally of the body to facilitate this adjustment.

After this has been done the customer is asked as to which of the springs should be adjusted to provide for greater comfort. Such adjustment is made in accordance with the comfort desired by the customer, after which if the bed spring to be constructed is for a double bed the user of the other side of the bed will be asked to recline on the mattress and an adjustment will be made for that side of the bed spring.

The gauge marks on the indicator bar 33 before referred to are read after each complete adjustment has been made and a record is made thereof and the bed spring is built accordingly. If the green band is opposite any pointer 34, it will indicate that the springs in the corresponding section of the bed spring should be of the stiffness indicated by the pointer. If the red band is opposite any pointer, it will indicate that a less stiff spring should be used in the corresponding section of the bed spring, etc. and to facilitate carrying out this invention a supply of green, red, white and blue springs of corresponding stiffness or gauge will be kept in stock.

It is to be noted that the apparatus disclosed is not a bed spring but a separate apparatus and that an individualized bed spring may be built merely by the use of springs of the same color as that indicated by the pointer after the apparatus has been adjusted. The encircling springs of the bed spring will be made of standard gauge and stiffness.

It is obvious that this invention is applicable to the manufacture of various types of cushioning devices such as mattress, seat and back cush-

ions, etc. and that the apparatus illustrated for purposes of disclosure may be used to gauge the springs for seats, seat cushions as well as mattresses and bed-springs, etc. The term "bed-spring" as used in certain of the claims is not used in a limiting sense but is intended to cover the full range of equivalents. It is obvious that the invention may be carried out by other means and that other forms of resilient means and adjusting and indicating means could be used.

While but one form of apparatus has been disclosed for carrying out one step in the method of constructing a bed-spring to fit the individual customer, it is to be understood that the apparatus disclosed may be modified and that we reserve the right to such changes in the means employed as fall within the principles of this invention and the scope of the appended claims.

What is claimed is:

1. In an apparatus of the character described, comprising a frame, a series of springs arranged in transverse rows, a movable support for the lower ends of each row of springs, a toggle connection between said support and said frame, means for opening and closing said toggle to raise and lower the support for said springs, and means bearing upon the upper ends of the springs and connected to the frame for preventing upward movement of the upper ends of said springs as the lower ends are raised.

2. In an apparatus of the character described, comprising a frame, a series of springs arranged in transverse rows, a movable support for the lower ends of each row of springs, a toggle connection between said support and said frame, means for opening and closing said toggle to raise and lower the support for said springs, and means bearing upon the upper ends of the springs and connected to the frame for preventing upward movement of the upper ends of said springs as the lower ends are raised, said means for opening and closing said toggles comprising a bar connected to the joints of said toggles, a threaded member pivotally connected to said bar, a second threaded member cooperating with said first threaded member and a bracket on the frame in which said second threaded member is supported for rotation and against longitudinal movement.

3. In an apparatus of the character described, comprising a frame, a series of springs arranged in transverse rows, a movable support for the lower ends of each row of springs, and a toggle connection between said support and said frame, means for opening and closing said toggle to raise and lower the support for said springs, means bearing upon the upper ends of the springs and connected to the frame for preventing upward movement of the upper ends of the springs as the lower ends are raised, said means for opening and closing said toggles comprising a bar connected to the joints of said toggles, a threaded member pivotally connected to said bar, a second threaded member cooperating with said first threaded member and a bracket on the frame in which said second threaded member is supported for rotation and against longitudinal movement, an indicating bar connected to the frame and projecting upwardly along the side of the support for the springs, and means on said support and said indicating bar indicating the compression of the springs and the stiffness of the springs to be located in a corresponding section of the bed spring.

4. In an apparatus for determining the stiffness of springs required in different sections of a bed spring for use in the construction of individualized bed springs, comprising a frame, a series of springs arranged in transverse rows, a movable support for the lower ends of each row of springs, an adjustable supporting linkage between the support for each row of springs and the frame, means for varying the supporting

linkage adjustment for each row of springs to raise and lower the support for the springs, and means bearing on the upper ends of the springs and connected to the frame for preventing upward movement of the upper ends of said springs as the lower ends are raised, and means for indicating said stiffness.
